(57) **CLAIM**

(21) Appl. No.: **29/564,977**

The ornamental design for a circular canopy for light fixtures, as shown and described.

(22) Filed: **May 17, 2016**

DESCRIPTION

(51) LOC (10) Cl. **26-99**

FIG. 1 is a perspective view of the circular canopy for light fixtures showing my new design;

(52) U.S. Cl.

FIG. 2 is a front elevational view thereof, the rear elevational view being a mirror image;

USPC **D26/142**

FIG. 3 is a right side elevational view thereof, the left side elevational view being a mirror image;

(58) **Field of Classification Search**

FIG. 4 is a bottom plan view thereof;

USPC D26/76, 78, 79, 80, 81, 82, 83, 85,

FIG. 5 is a perspective view of a second embodiment of my new design;

88, D26/90, 93, 110, 118, 119, 120, 121,

FIG. 6 is a front elevational view thereof, the rear elevational view being a mirror image;

122, 138, D26/140-142

FIG. 7 is a right side elevational view thereof, the left side elevational view being a mirror image; and,

CPC F21S 4/00; F21S 4/003; F21S 4/006;

FIG. 8 is a bottom plan view thereof.

F21S 4/007; F21S 4/008; F21S

The top plan view of each embodiment is being plain and devoid of any ornamentation.

6/004; F21S 6/005; F21K 9/54; F21V

The break lines in FIGS. 1-3 and 5-6 indicate that the appearance of any portion of the canopy between the break lines forms no part of the claimed design.

15/01; F21V 15/013

The broken lines in the drawings illustrate portions of the circular canopy for light fixtures which form no part of the claimed design.

See application file for complete search history.
